OTTO E. UHLMANN, OF GRAND RAPIDS, MICHIGAN, ASSIGNOR TO KEELER BRASS COMPANY, OF GRAND RAPIDS, MICHIGAN

DESIGN FOR A DOOR PULL

Application filed July 21, 1930. Serial No. 36,412. Term of patent 3½ years.

To all whom it may concern:

Be it known that I, OTTO E. UHLMANN, a citizen of the United States, residing at the city of Grand Rapids, in the county of Kent and State of Michigan, have invented a new, original, and ornamental Design for a Door Pull, of which the following is a specification, reference being had to the accompanying drawing, forming a part thereof.

Fig. 1 is a side elevational view, and Fig. 2 is a front elevational view of a door pull, showing my new design.

I claim:
The ornamental design for a door pull, as shown.

OTTO E. UHLMANN.
